DESIGN FOR A COMBINED POWDER BOX AND BRUSH HOLDER

Erich Neumann-Holste, Bielefeld, Germany

Application September 12, 1934, Serial No. 53,260 1/2

Term of patent 14 years

To all whom it may concern:

Be it known that I, Erich Neumann-Holste, a citizen of the Republic of Germany, residing at Bielefeld, in the State of Prussia, Germany, whose post-office address is Sudbrackstrasse, Bielefeld, Germany, have invented a new, original, and ornamental Design for a Combined Powder Box and Brush Holder, of which the following is a specification, reference being had to the accompanying drawing, forming part thereof.

Figure 1 is a plan view of the top of the combined box and brush holder showing my new design; and

I claim:—

The ornamental design for a combined powder box and brush holder as shown.

ERICH NEUMANN-HOLSTE.
